POURING DEVICE

Louis A. Camerota, Burlington, N. J., assignor
to Florence Pipe Foundry & Machine Company,
Florence, N. J., a corporation of New Jersey

Application July 20, 1935, Serial No. 32,322

10 Claims. (Cl. 22—79)

This invention relates to pouring devices and is particularly applicable to the charging of molds on a centrifugal casting machine. It deals with problems involved in the handling of molten metal immediately prior to and during the discharge of the metal into a rotating flask.

The principal object of the invention is to provide a mechanically actuated pouring device, relatively simple and efficient in its operation, with the parts thereof so designed that their movements can be controlled with facility and safety by a relatively unskilled operator.

A more specific object of the preferred form of the invention is to provide a self-contained pouring unit incorporated within a movable carriage and including a tiltable ladle and various instrumentalities for operating the ladle and its carriage, such instrumentalities being mounted on and forming a part of the carriage.

Another object of the invention is to provide novel means for mounting a tilting ladle of the character described upon a supporting carriage, together with a specially designed lip for the ladle, for the purpose of effecting an even flow of metal from the ladle to the discharge spout and thence to the mold to be charged, the apparatus being particularly designed to prevent surging or splashing.

Still other objects of the invention include the provision of means for controlling the operation of the ladle and its carriage from a remote station, the provision of means permitting ready removal of the ladle and the discharge spout, and means for adjusting the relative positions of the ladle and spout.

The advantages characterizing the pouring device of my invention will become more fully apparent from the description hereinafter set forth of one embodiment or example of the invention, having reference to the accompanying drawings.

40 Of the drawings:

Fig. I represents a plan view of a ladle carriage embodying my invention.

Fig. II represents a side elevation of the same, showing the ladle in its normal position.

45 Fig. III represents a view similar to Fig. II, with parts of the ladle carriage and the ladle shown in cross section, taken as indicated by the lines III—III of Fig. I.

50 Fig. IV represents a view partly in side elevation and partly in section of the ladle and ladle carriage showing the ladle elevated to its maximum angle of tilt.

Fig. V represents a cross section, taken as indicated by the lines V—V of Fig. II, showing the

manner in which the ladle carrying bracket is pivotally mounted on the carriage frame.

Fig. VI represents a cross section, taken as indicated by the line VI—VI of Fig. II, illustrating the manner in which the ladle tilting cylinder is pivotally mounted on the carriage frame.

Fig. VII represents a view partly in side elevation and partly in cross section, showing the operating cylinder for moving the ladle carriage.

Fig. VIII represents a view partly in side elevation and partly in cross section, showing the details of the cylinder employed for tilting the ladle.

Fig. IX represents a cross section, taken as indicated by the lines IX—IX of Fig. I, showing the manner in which the carriage operating cylinder is incorporated within the carriage.

Fig. X is an enlarged cross section of one end of the carriage operating cylinder, showing details thereof; and,

Fig. XI is a diagrammatic representation of the pressure lines and the valves employed for controlling operation of the tilting cylinder and carriage operating cylinder.

With reference particularly to Figs. I and II, there is shown in the drawings, a pouring assembly comprising generally a tiltable ladle 1, a ladle carrying stirrup 2 pivoted on spaced frame members 3 of a movable carriage 4, and a connecting spout 5 adapted to convey molten metal from the mouth of the ladle to the end of a rotary flask (not shown) of a centrifugal casting machine.

The ladle carriage 4 has wheels 6 engaging the rails 7 of a track which leads to the casting station. As shown in Fig. IX, the wheels 6 of the ladle carriage 4 may be formed with V-shaped grooves and the rails 7 constructed of angle bars fitting said grooves, though the particular form of the wheels and track is not material to the present invention. In order to reciprocate the ladle carriage along the track rails 7, and thus to move the connecting spout 5 towards or away from the casting station, an operating cylinder 8 is employed, this cylinder being incorporated within the ladle carriage 4 and having relative movement with respect to a plunger 9 which is maintained in fixed relation to the track rails. The stroke of the plunger 9 within the cylinder 8 represents the limit of travel of the ladle carriage 4.

The ladle carriage 4 consists of a framework conveniently built up of channel bars 12 extending longitudinally and transversely and supporting a platform 13. As shown in Fig. IX, the operating cylinder 8 for moving the ladle carriage 4

20

25

30

35

40

45

50

55

is rigidly incorporated within the framework and attached thereto by means of screw bolts 11 and angle brackets 14.

As most clearly shown in Fig. VII, the operating cylinder 8 has a stuffing box 15 at one end thereof, and a removable head 16 at the opposite end. The plunger 9 terminates in a plunger head 17, the details whereof are shown clearly in Fig. X. The plunger head 17 is fitted with suitable packing 18 and is rigidly secured to the plunger 9 by pins 19. Within the plunger 9 there is an internal pipe 20 which leads through the plunger head 17 and admits the pressure medium to the space between the plunger head 17 and the cylinder head 16. An annular space 21 is provided between the internal pipe 20 and the plunger 9 into which the pressure medium is admitted by means of a pipe connection 22. Adjacent to the plunger head 17 ports 23 are provided leading 10 from the annular space 21 to an outer annular space 24 defined between the plunger 9 and the cylinder 8. In an obvious manner, when the pressure medium is admitted through the internal pipe 20 to the space 25 between the plunger head 17 and the cylinder head 16, the cylinder 8 is caused to move to the right as viewed in Fig. 15 VII. On the other hand, when the pressure medium is admitted through the pipe connection 22 to the annular space 21 within the plunger 9, the 20 medium escapes through the ports 23 to the annular space 24 and causes the cylinder 8 to move to the left. Accordingly, the direction of movement of the ladle carriage 4 is dependent upon whether the pressure medium is supplied at the 25 internal pipe 20 or at the pipe connection 22. An additional pipe connection 27 is provided adjacent to the stuffing box 15 and communicating with the annular space 24. As hereinafter described, the pipe connection 27 leads to the tilting cylinder 28.

As shown most clearly in Fig. IV, the plunger 9 is supported at its outward end upon a standard 29 secured to the foundry floor adjacent to the ends of the track rails 1. Desirably there is also 45 provided adjacent to the standard 29 a stop block 30 which projects upwardly above the rails 1 and which serves to limit the movement of the ladle carriage 4 towards the casting station. Above the platform 13 of the ladle carriage 4, and rigidly secured thereto, are the spaced frame members 3, these members being of substantially triangular shape and affording vertical walls at each side of the ladle carriage. The ladle carrying stirrup 2 comprises two pairs of arms 31 in the form of 50 flat plates pivotally attached by means of trunnions 33 to the top corners of the frame members 3. The arms 31 are cross connected by means of a transversely disposed plate 34.

The ladle 1 is removably supported on the ladle carrying stirrup 2 in the following manner. The ladle is provided at each side with a hook shaped gusset 35 which surrounds the top edge of the transverse plate 34 of the ladle carrying stirrup 2. An oppositely disposed hook shaped projection 36 60 affixed to the bottom of the ladle carrying stirrup 2 at each side thereof engages pins 37 projecting laterally from the sides of the ladle. The ladle is thus held by its own weight upon the ladle carrying stirrup 2, but is readily removable 65 by raising it in a vertical direction which may be accomplished by applying a lifting tackle to a bail 48 attached to the top of the ladle. The ladle 1 has an upwardly and forwardly inclined wall 41 and a rear wall 42 which is substantially 70 arcuate in cross section. At the mouth of the

ladle the inclined wall 41 terminates in a pouring lip 43 of rounded formation, the forward edge of the pouring lip being substantially coincident with the axis of the aligned trunnions 33 and their bearings 44. Immediately in the rear of the 5 curved portion of the lip 43 there is provided a shoulder 45 which serves as a dam or weir restricting the flow of metal. The ladle 1 is lined with suitable refractory material as indicated at 46 and is encased within a box-like framework 47. An inclined plate 38 disposed beneath the lip 43 serves as a guard for deflecting any spilled metal away from the tilting cylinder 28.

At the mouth of the ladle 1 there is preferably provided a skimming device comprehensively designated at 48, which includes a blade 49 in the form of a flat plate normally maintained in a position within the mouth of the ladle with its bottom edge extending downwardly to a predetermined distance above the surface over which the 20 metal is poured and at a predetermined distance in the rear of the shoulder 45. By means of a handle 50, the skimming device including the blade 49 may be swung to a position outside the ladle, as indicated in the drawings by broken 25 lines. The skimming device pivots about a shaft 51 and includes arms 52, 53, which are adapted to engage a pin 54. When the arm 53 engages the pin 54, the blade 49 is maintained in its normal position within the mouth of the ladle. When 30 the handle 50 is manipulated to swing the skimming device to reverse position, the arm 52 engages the pin 54 and the skimming device is maintained outside the ladle in a position where 35 it is accessible for cleaning. The detailed construction of the skimming device 48 is more fully described in my pending application for U. S. Letters Patent, Serial No. 32,321 filed July 20, 1935.

The manner in which the ladle carrying stirrup 2 is pivoted upon the spaced frame members 3 of the ladle carriage is shown most clearly in Fig. V, and it will be noted that the forward edge of the pouring lip 43 of the ladle is substantially coincident with the axis about which the ladle 45 pivots and is disposed immediately above the trough of the connecting spout 5. A special advantage of this construction is that the molten metal carried within the ladle 1 is adapted to flow smoothly and without surging or splashing 50 from the ladle 1 to the connecting spout 5. Accordingly in specifying herein that the forward edge of the lip of the ladle is "substantially coincident with the axis about which the ladle pivots" it is meant that incident to the tilting of 55 the ladle a relation is maintained between the forward edge of the lip 43 and the connecting spout 5 which does not materially alter the drop of the metal as it flows from the ladle to the spout. Desirably the connecting spout 5 is rendered adjustable and removable. For this purpose the connecting spout 5 has at its upper end a pair of laterally extending pins 55 which are engaged by hook shaped adjustable brackets 56 mounted on the frame members 3. Similarly at 60 its lower end the connecting spout 5 has a pair of depending lugs 57 adapted to rest upon a bar 58 which in turn is carried by a pair of adjustable brackets 59. The brackets 56, 59 are slotted and secured to the frame members 3 by bolts 60, 61, 65 and in this manner the brackets are rendered adjustable so that the connecting spout 5 may be positioned in the desired relation to the lip 43 of the ladle 1 and to the end of the rotary flask 70 to be charged. Moreover, it is relatively simple 75

to adapt the pouring assembly to different size flasks by substituting one type of connecting spout for another.

The tilting cylinder 28 employed for raising and lowering the ladle 1 is shown in detail in Figs. VI and VIII. It will be particularly observed that the tilting cylinder 28 is provided with laterally extending trunnions 62 which engage aligned bearings 63 in the spaced frame members 3. Within the cylinder 28 there is a plunger 64 which has at one end a head 65 and which at the opposite end is pivoted by means of a pin 66 to the ladle-carrying stirrup 2. It will be noted that the pivotal attachment of the plunger 64 to the stirrup 2 establishes a connection between the plunger 64 and ladle 1 which is direct in the sense that it avoids the use of intermediate links or moving parts, or parts subjected to wear and hence likely to develop play between them. A stuffing box 67 surrounds the plunger 64 where it enters the cylinder 28. As shown most clearly in Fig. VI, the fluid medium for operating the tilting cylinder 28 enters the cylinder through a pipe connection 68 disposed centrally of one of the trunnions 62. It passes through a port 69 into the interior of the cylinder 28. The plunger head 65 is constructed of less diameter than the internal diameter of the cylinder 28 permitting the fluid medium to pass around the head 65, and by action upon the relatively large surface of the plunger head 65 to force the plunger to the right shown by the dotted lines in Fig. VIII. Accordingly, whenever pressure is admitted through the pipe connection 68, the plunger 64 is extended to raise the ladle 1, and when such pressure is relieved through the same connection the weight of the ladle 1 returns the plunger 64 to its normal position. Adjacent to the trunnions 62 the cylinder 28 is desirably provided with reinforcing webs 70, 71 disposed longitudinally and transversely, respectively.

The normal position of the ladle 1 is shown in Figs. I and II. When the cylinder 28 is operated to lift the ladle 1 to its maximum angle of tilt, the parts assume the position represented in Fig. IV. The fluid medium exhausted from the carriage operating cylinder 8 through the pipe connection 27 passes to a pipe line 72 and leads to a stop valve 74. Beyond the stop valve 74 there is provided a by-pass 75 which has therein a regulating valve 76, adjustable by means of an arm 77, which governs the flow to the tilting cylinder 28 and hence the rate of movement of the tilting cylinder. Desirably a check valve 78 is disposed in parallel relation with the regulating valve 76. A pipe connection 79 leads from the region of the by-pass 75 to an automatically controlled valve 80 and an additional line 81 leads from the automatic control valve 80 to the pipe connection 68 at one of the trunnions 62 of the tilting cylinder 28. Thus it will be observed that the carriage operating cylinder 8 and the tilting cylinder 28 are disposed in series relation. The check valve 78 permits only return flow of the fluid medium from the tilting cylinder so that when this cylinder is exhausted the medium bypasses the regulating valve 76.

The piping diagram showing the controls for the operation of the carriage operating cylinder 8 and tilting cylinder 28 is shown in Fig. XI. A master control valve 82 is disposed remotely from the ladle carriage 4 and preferably situated at the operator's station of the centrifugal casting machine. The master control valve 82 is provided with a handle 83, and in the present

illustration it may be assumed to be a four-way valve. When the handle 83 is in the position shown in Fig. XI, the fluid medium in the supply line 84 passes through the valve in the direction indicated by the arrows to the pipe line 85, and thence to the carriage operating cylinder 8. Moreover, the exhaust from the carriage operating cylinder 8 passes through the pipe line 86, through the master control valve in the direction indicated by the arrow to the exhaust line 87. When the position of the handle 83 of the master control valve 82 is reversed, the fluid medium passes directly from the pipe line 84 to the pipe line 86 and is exhausted directly through the pipe lines 85 to the pipe line 87.

To accomplish the automatic tilting of the ladle 1 when and only when the ladle carriage 4 is in proper position at the casting station, the automatic control valve 80 is provided. As shown most clearly in Fig. IV, the automatic control valve 80 has an operating lever 88 fulcrumed at a fixed pivot 89 and is pivotally attached to the stem 90 of the valve 80. The operating lever 88 projects beneath the ladle carriage 4 and is adapted to strike a projecting block 91 disposed adjacent to the rails 7. In an obvious manner, when the lever 88 strikes the block 91, the stem 90 is moved outwardly to open the valve 80. The lever 88 is thus moved against the pressure of a spring bumper 92 secured to the ladle 1. The projecting block 91 is disposed at a predetermined point along the track rails 7 in such manner when the ladle carriage 4 is moved to the casting station and the connecting spout 5 has entered the rotary flask of the casting machine, the valve 80 will open. Upon the raising of the ladle 1, the opening of the valve 80 causes pressure to be admitted to the tilting cylinder 28 and the valve 80 is not again closed until the return of the ladle 1 to its normal position brings the spring bumper 92 into contact with the end of the stem 90 of the valve 80.

More specifically, the operation of the apparatus of this invention is as follows. Let it be assumed that the ladle carriage 4 is in the position represented in Fig. II with the head 17 of the plunger 9 at the left hand end of the carriage operating cylinder 8, the position in which the ladle carriage is farthest away from the casting station. Let it also be assumed that the ladle 1 is in its normal lowered position and that the operator desiring to charge the rotary flask of a casting machine moves the handle 83 of the master control valve 82 to the position represented in Fig. XI. The pressure medium then passes through the line 84 and through the valve 82, as indicated by the arrows, to the line 85, and thence through the pipe connection 22 into the annular space 21 between the internal pipe 20 and the plunger 9. Under these circumstances there is a relative movement of the plunger head 17 to the right, or a movement of the carriage operating cylinder 8 to the left. This is accompanied by a passage of a portion of the fluid medium through the ports 23 into the outer annular space 24 of the cylinder 8, and through the connection 27 to the pipe line 72, and thence through the regulating valve 76. The automatic valve 80 being closed, however, the tilting cylinder 28 does not operate at this point.

The movement of the ladle carriage 8 toward the casting station continues to the limit of the travel of the plunger 9 within the cylinder 8. Immediately before the plunger 9 reaches its limit of travel, the operating lever 88 of the valve 80 strikes the projecting block 91 alongside the

track rails 7 and causes the valve 80 to open. Thus when the ladle carriage 4 reaches the proper position, the fluid medium passes through the valve 80 to the pipe connection 68 on the tilting cylinder 28 and through one of the trunnions 62 of that cylinder into the interior space thereof. The fluid medium passes around the plunger head 65 and forces the plunger 64 to the right, causing the ladle 1 to be elevated. When the ladle 1 reaches its maximum limit of tilt, as represented in Fig. IV, and the contents thereof are charged through the connecting spout 5 into the end of the rotary flask on the casting machine, the operator, desiring to return the ladle 1 and ladle carriage 4 to their original position, reverses the master control valve 82 by movement of the operating lever 83. Under these circumstances, the pressure is admitted through the line 84 directly to the line 86 and from thence to the internal pipe 20 of the plunger 9. The fluid medium passes to the right hand end of the cylinder 8 and operates against the plunger head 17, forcing the cylinder 8 to the right. The ladle carriage 4 continues to move to the right, to the limit of its travel. At the same time, the weight of the ladle 1 causes the plunger 64 of the tilting cylinder 28 to return to its normal position, forcing fluid medium out of the cylinder 28 through the connection 68 and the pipe line 81, and through the automatic valve 80 (which is still in open position) and through the check valve 78 and line 72 into the annular space 24 of the carriage operating cylinder 8. The fluid medium is exhausted through the ports 23 into the annular space 21, and thence through the pipe connection 22 into the pipe line 85, and thence directly through the master control valve 82 to the exhaust line 87. As the tilting ladle 1 returns to its lowered position, the spring bumper 92 thereon strikes the stem 90 of the valve 80 and closes the valve. The ladle carriage 4 is thus in readiness for further operation.

It will be observed that the ladle carriage of this invention constitutes a self-contained unit, all of the operations of which are remotely controlled, thus avoiding the necessity for there being any attendant at the ladle carriage, all of the operations being controlled by an attendant at the casting station. Moreover, the automatic raising and lowering of the ladle 1 as an incident to the movement of the carriage 4, is a safety feature which prevents accidental discharge of the contents of the ladle. The ladle 1 can only be operated when the carriage 4 is in the position at the casting station, or when the connecting spout 5 is disposed within the end of the rotary flask.

Many additional advantages of the pouring device of this invention follow from the use of the particular mounting by which the ladle is carried on the framework of the ladle carriage, and the mechanism by which the ladle is caused to be raised and lowered. The unit being self-contained and the ladle being operated by mechanism mounted on the carriage, there is no necessity for the use of cables or other external devices. Furthermore, the ladle mounting is such that the desired relationship is established between the mouth of the ladle and the spout, and an even, smooth, flow of metal, without appreciable drop or surging or splashing, is provided from the ladle to the connecting spout. Whenever desired, the ladle 1 may be readily removed for cleaning or repair, and the connecting spout

5 may also be removed or adjusted at convenience.

While I have described my invention in considerable detail and with reference to one particular embodiment thereof, it will be apparent that various changes may be made in the form of the apparatus herein described and illustrated, and that certain features of the invention may at times be used to advantage without a corresponding use of other features, all without departing from the spirit of my invention as defined in the annexed claims.

Having thus described my invention, I claim:

1. A pouring device of the character described comprising a carriage having spaced frame members thereon, a ladle-carrying stirrup pivoted on said frame members, a ladle removably attached to said stirrup with the mouth thereof extending between said frame members, and means for tilting said ladle including a cylinder pivotally mounted on said carriage and a plunger in said cylinder pivotally attached to said ladle-carrying stirrup.

2. A pouring device of the character described comprising a carriage having spaced frame members thereon, a ladle mounted for tilting movement about said frame members, the mouth of said ladle extending between said frame members and terminating in a lip having its forward edge substantially coincident with the axis about which the ladle is tilted, and means for tilting said ladle including a cylinder pivotally mounted on said carriage and a plunger in said cylinder having a direct pivotal connection with said ladle.

3. A pouring device of the character described comprising a carriage, a ladle mounted for tilting movement on the carriage frame, means for tilting said ladle including a cylinder having laterally extending trunnions whereby it is pivoted to said carriage, a plunger in said cylinder having a direct pivotal connection with said ladle, and a line for a pressure medium leading to said tilting cylinder through one of the trunnions aforesaid.

4. A pouring device of the character described comprising a carriage, a ladle mounted for tilting movement on the carriage frame, means for tilting said ladle including a cylinder having laterally extending trunnions whereby it is pivoted to said carriage, a plunger in said cylinder having a direct pivotal connection with said ladle, a supply line for a pressure medium leading to said tilting cylinder through one of the trunnions aforesaid, and an exhaust line for said medium leading away from said cylinder through the other trunnion.

5. A pouring device of the character described comprising a movable carriage, an operating cylinder incorporated in the frame of said carriage and serving to move the same in the direction of its length, a ladle mounted for tilting movement on an axis disposed transversely of the carriage, and means for tilting said ladle comprising a second cylinder pivotally attached to the carriage, and a plunger in said second cylinder having a direct pivotal connection with said ladle.

6. A pouring device of the character described comprising a movable carriage, an operating cylinder incorporated in the frame of said carriage and serving to move the same in the direction of its length, a ladle mounted for tilting movement on an axis disposed transversely of the carriage, means for tilting said ladle comprising a second cylinder mounted on the carriage, said second

cylinder operating in series with the first cylinder whereby the ladle when filled with metal may not be tilted until the first cylinder has completed its operation.

- 5 7. A pouring device of the character described comprising a ladle carriage guided for reciprocatory movement, a ladle mounted on said carriage and adapted to tilt about an axis disposed transversely to the path of movement of said carriage, a cylinder on said carriage for tilting said ladle, a remotely controlled cylinder on said carriage for reciprocating said carriage, a valve for controlling said ladle tilting cylinder and means disposed in the path of movement of said carriage 10 15 for operating said valve when the carriage reaches a predetermined point in its movement.

8. A pouring device of the character described comprising a track, a ladle carriage movable on said track, a ladle mounted on said carriage and 20 25 adapted to tilt about an axis disposed substantially transversely to said track, means on said carriage for tilting said ladle, a valve for controlling said ladle tilting means, and means including an element disposed alongside said track for operating said valve when the carriage reaches a predetermined point on said track.

9. In combination, a casting station, a track

leading to said casting station, a ladle carriage movable on said track, a ladle mounted on said carriage, a pressure cylinder on said carriage for tilting said ladle, a valve for controlling the operation of said pressure cylinder, a projecting 5 member alongside said track, and a lever on said carriage adapted to strike said projecting member and to operate said valve when said carriage is moved to said casting station thereby to raise the ladle to pouring position. 10

10. In combination, a casting station, a track leading to said casting station, a ladle carriage movable on said track, a ladle mounted on said carriage, a pressure cylinder on said carriage for tilting said ladle, a valve on said ladle carriage 15 20 25 for admitting the pressure medium to said pressure cylinder to raise said ladle, a remote master control valve for exhausting said pressure cylinder to lower the ladle, means for automatically opening said valve on the ladle carriage when the carriage is moved to the casting station, and means for automatically closing said valve on the ladle carriage when the ladle is lowered as the result of the operation of the master control valve aforesaid. 25

LOUIS A. CAMEROTA.
